UNITED STATES PATENT OFFICE

2,564,420

SKI APPARATUS

Robert Paul Brown, White Plains, N. Y.

Application April 20, 1948, Serial No. 22,182

9 Claims. (Cl. 280—21)

1

This invention relates to a novel ski and a novel handle arrangement for interconnecting a pair of skis to provide a sled-like arrangement permitting relative angular displacement of the skis for steering purposes.

In the present arrangement, a pair of skis of novel construction are interconnected by a quickly detachable handle frame, which is pivotally connected to the skis so that the frame may be moved between an upright, supporting position and a collapsed position, the elements of which frame can be quickly disconnected from each other and from the skis for compact, economical storage.

A novel arrangement is provided for maintaining the skis in fixed lateral relation while providing for a relative angular displacement of the skis. For this purpose, each ski has a transverse sleeve at its forward end which receives a tubular bearing end on a handle. The handles are of tubular construction, including an intermediate elongated portion and reversely directed bent ends. One bent end of each handle is inserted in a sleeve on a ski so that it projects thereinto in a laterally inward direction. This engagement provides the pivotal connections between the handles and the sleeves.

A pair of clamps interconnect the elongated portions of the handles, and each clamp preferably comprises a pair of substantially flat plates having mating, semi-cylindrical offsets receiving the handles. The plates are clamped together by suitable quick acting means such as wing nut and bolt arrangements.

The arrangement thus far described provides for oscillation of the handle bearing portions, and the skis, about the elongated handle portions as axes. To limit such oscillation and prevent disengagement of the handles from the skis, a spreader is provided. This spreader is in the form of a rod extending between the inner ends of the handle bearing portions and having offset ends fitting therein. These offset ends prevent laterally inward displacement of the ski sleeves from the handle bearing portions. Additionally, the diameter of the spreader rod is much smaller than the inner diameter of such bearing portions. Consequently, the offset ends of the spreader have loose fits in the bearing portions, permitting relative oscillation of the offset ends and the bearing portions. This provides for relative angular movement of the skis for steering purposes while, at the same time, limiting the extent of such angular movement.

Another novel feature is a combined foot plate and brake mounted on each ski in such position

2

that, when a skier stands on the foot plates and grasps the handle frame in the upright position, the skier is in the usual skiing posture. For this purpose, a saddle is mounted intermediate the ends of each ski and pivotally supports a foot plate for vertical oscillation thereof. The pivotal mounting is nearer the rear end of the foot plate so that the skier normally tilts the plates forwardly. A snow engaging fin is formed on or secured to the rear end of each plate, so that the skier can tilt the plates rearwardly to engage the fin in the snow to brake the skis either together or separately. This action is assisted by the supporting action of the handle frame.

15 The skis, per se, are of a novel tubular construction, greatly increasing the strength-weight ratio. The snow engaging surface is formed by the base of an elongated channel having its flanges formed with reentrant portions. An 20 elongated, transversely arched, upper member has flanges interfitted or interlocked with the reentrant portions to provide a tubular cross-section for the skis.

It is therefore among the objects of this invention to provide a novel, tubular ski.

Another object is to provide a novel sled-like arrangement incorporating a pair of skis and a handle frame detachably interconnecting the skis against lateral displacement while providing for 30 relative angular displacement of the skis.

A further object is to provide a novel braking and foot plate arrangement for the sled-like arrangement, coordinated with the handle frame.

These, and other objects, advantages and novel 35 features of the invention will be apparent from the following description and the accompanying drawings.

In the drawings:

Fig. 1 is a front elevation view of a device 40 embodying the invention.

Fig. 2 is a side elevation view thereof.

Fig. 3 is a partial, longitudinal sectional view on the line 3—3 of Fig. 1.

Fig. 4 is a sectional view on the line 4—4 of Fig. 45 1, showing the oscillation limiting pivotal connection.

Fig. 5 is a longitudinal sectional view through the foot plate and brake arrangement.

Fig. 6 is a transverse sectional view on the line 50 6—6 of Fig. 5.

Figs. 7 and 8 are plan views of the device with the skis parallel and angularly displaced, respectively.

Referring to the drawings, the ski-sled type device of the invention is illustrated at 10 as comprising a pair of substantially identical skis

15, 15' interconnected by a handle structure generally indicated at 50. Handle structure 50 maintains skis 15, 15' against lateral displacement while permitting relative angular displacement of the skis. Additionally, each ski carries, intermediate its ends, a foot plate 35 or 35', which is mounted for vertical oscillation and carries a snow engaging brake fin 45, 45'. Foot plates 35, 35' are so located that a skier standing on the foot plates can readily grasp handle structure 50 when the skier is in the usual skiing posture.

Skis 15, 15' are of a novel tubular construction, and as the skis are identical in construction, only ski 15 will be described in detail. The 15 ski includes a lower elongated channel member 16 whose base 17 acts as the snow running face of the ski and has suitable means, such as a groove 18 (Fig. 6), stabilizing the ski against lateral sliding movement. The flanges 19 of channel member 16 are bent inwardly to form reentrant portions 21 spaced slightly from the flanges.

The ski also includes an upper, transversely arched, elongated member 26 which has longitudinal flanges 27 interfitting with reentrant portions 21 of flanges 19. The two interlocked members 16 and 26 form a tubular, reinforced structure for ski 15.

Channel 16 has an upturned forward end 22, which forms the toe of the ski, and base 17 is continued beyond flanges 19 and curled on itself to form a sleeve 25 for a purpose to be described. The forward end of arched member 26 has flanges 28 which are riveted or otherwise secured to toe 22, and the rear end is flattened and bent down into channel 16, as at 29, to close the rear end of the tubular structure. Thus, a completely enclosed, hollow tubular structure is provided for the ski. The same reference numerals, primed, have been used to designate the corresponding elements of ski 15'.

Intermediate the ends of ski 15, a channel shaped saddle 36 is riveted or otherwise secured to arched member 26. For this purpose, the base of channel 36 has an arched portion 37 conforming to member 26 and flattened portions 38 resting on the reentrant flange portions 21 of member 16. The flanges 39 of channel saddle 36 are triangular, and the apex of each flange supports a rivet 41 acting as a bearing for foot plate 35.

Foot plate 35 is a channel member whose base 42 has longitudinal anti-slip grooves 43. Flanges 44 are deeper at the rear end and are continued around the forward end of the foot plate as at 46 (Fig. 7), and around the rear end as at 47. A shoe conforming structure is thus provided, and struck out loops 48 may receive straps to secure the skier's foot to the foot plate. Snow engaging brake fin 45 has a flange 49 secured to the rear part of plate 35 by rivets or the like.

It will be noted that the pivotal support for plate 35 on saddle 36 is nearer the rear end of the plate so that the skier normally tends to tip the plate forward, retracting fin 45. The plate is so located that a skier standing thereon and grasping handle structure 50 naturally assumes the usual skiing posture. Thus, when braking is desired, the skier can force himself backward by the handle structure to tilt plate 35 rearwardly to dig fin 45 into the snow.

Handle structure 50 is an important feature of the invention, and includes a pair of handles 55, 55' of tubular material. The lower end of

each handle has an inwardly bent bearing portion 56, 56' inserted into sleeves 25, 25' in a laterally inward direction and having close bearing fits therein. The upper ends 57, 57' of the handle are bent outwardly to form handles, and may have grips 58, 58' thereon. It will be noted that handles 55, 55' are thus hinged to skis 15, 15' and may be swung from a collapsed position adjacent the skis to an upright position or even to a towing or drawing position.

Lateral outward displacement of handles 55, 55' and thus of skis 15, 15' is prevented by clamps 60, 65. Clamp 60 includes a pair of plates 61, 62 having matching semi-cylindrical grooves or offsets 63, 63' each embracing one of the handles 55, 55'. Plates 61, 62 are clamped on the handles by suitable quick acting means such as thumb nut and bolt arrangements 64, 64'. Similarly, clamp 65 includes a pair of plates 66, 67 having matching semi-cylindrical grooves or offsets 68, 68' and clamped together onto handles 55, 55' by wing nuts 69, 69'. For strengthening purposes, the plates of both clamps may be embossed as shown in Figs. 1 and 3.

It will be noted that handles 55, 55' may oscillate about the axes of their intermediate portions, thus permitting angular movement of the skis relative to each other. This angular movement is limited, in a novel manner, by a spreader 70 which also prevents the skis from inward displacement relative to the handles. Spreader 70 is a bar or rod having a central portion 71 and offset ends 72, 72'. These ends, and preferably the entire bar 70, are of considerably less cross-sectional area than the internal area of handle ends 56, 56'. Consequently, when spreader ends 72, 72' are set into handle ends 56, 56', they have a loose fit therein (Fig. 4) so that the handle ends may be displaced angularly relative to the spreader ends by a limited amount. This permits relative angular movement of the skis, as may be seen from Figs. 7 and 8. The offset of ends 72, 72' from center portion 71 of spreader 70 is sufficient to provide abutments preventing inward lateral displacement of the skis.

Normally the device is carried in the knocked down state. To assemble it, handle ends 56, 56' are inserted into sleeves 25, 25' and spreader 70 has its ends 72, 72' set into the handle ends. The two clamps 60, 65 are then clamped to the handles by wing nuts 64 or 69. The skier straps his shoes onto foot plates 35, 35' and supports himself by handle structure 50. By turning one or both grips 58, 58', the skis may be angularly adjusted for steering purposes. To brake the skis, the skier tilts plates 35, 35' backward to dig brake fins 45, 45' into the snow.

The described device thus provides a novel, compact ski-sled arrangement which is steerable and brakeable. The skis may be angularly adjusted while still held in fixed lateral relation at the front end by spreader bar 70.

While a specific embodiment of the invention has been shown and described in detail to illustrate the application of the principle thereof, it will be understood that the invention may be otherwise embodied without departing from such principle.

What is claimed is:

1. A device of the class described comprising, in combination, a pair of skis; a pair of handles each connected to the forward end of a ski, each said handle having a sleeve; a frame interconnecting said handles against relative lateral displacement while providing for movement thereof.

to permit relative angular movement of the skis; and means extending between said skis and having end portions extending into and loosely mounted within the respective handle sleeves to limit the relative angular movement of the skis.

2. A device of the class described comprising, in combination, a pair of skis; a pair of handles each pivotally connected to the forward end of a ski, each said handle having a sleeve; a frame interconnecting said handles against relative lateral displacement while providing for movement thereof to permit relative angular movement of the skis; and means extending between said skis and having end portions extending into and loosely mounted within the respective handle sleeves to limit the relative angular movement of the skis.

3. A device of the class described comprising, in combination a pair of skis; a pair of handles each connected to the forward end of a ski, each said handle having a sleeve, said handles being swingable from an upright supporting position to a collapsed position adjacent said skis; a frame disengageably interconnecting said handles against relative lateral displacement while providing for movement thereof to permit relative angular movement of the skis; and removable means extending between said skis and having end portions extending into and loosely mounted within the respective handle sleeves to limit the relative angular movement of the skis.

4. A device of the class described comprising, in combination, a pair of skis; a pair of handles each pivotally connected to the forward end of a ski, each said handle having a sleeve, said handles being swingable from an upright supporting position to a collapsed position adjacent said skis; a frame disengageably interconnecting said handles against relative lateral displacement while providing for movement thereof to permit relative angular movement of the skis; and removable means extending between said skis and having end portions extending into and loosely mounted within the respective handle sleeves to limit the relative angular movement of the skis.

5. A device of the class described comprising, in combination, a pair of skis; a pair of handles each pivotally connected to the forward end of a ski, said handles being swingable from an upright supporting position to a collapsed position adjacent said skis; a frame interconnecting said handles against lateral displacement while providing for movement thereof to permit relative angular movement of the skis; means operatively associated with said handles and effective to limit the relative angular movement of the skis; a pair of foot plates each mounted, for oscillation in a vertical plane, intermediate the ends of one of said skis, said plates being so located that a user, standing upon said plates in the usual skiing posture, is effectively supported by grasping said handles in their upright position; and a snow engaging fin on each plate movable into operative engagement with the snow, to brake the skis, by oscillation of said plates.

6. A device of the class described comprising, in combination, a pair of skis; a pair of handles each pivotally connected to the forward end of a ski, said handles being swingable from an upright supporting position to a collapsed position adjacent said skis; a frame interconnecting said handles against lateral displacement while providing for movement thereof to permit rela-

tive angular movement of the skis; means operatively associated with said handles and effective to limit the relative angular movement of the skis; a pair of saddles each mounted on one of said skis intermediate the ends thereof; a pair of foot plates each pivoted on one of said saddles for oscillation in a vertical plane; the pivotal mounting for each plate being nearer to its rear end than to its front end so that a person standing on the plates tends to tilt them forwardly; and a snow engaging fin on the rear end of each plate movable into operative engagement with the snow, to brake the skis, by oscillation of said plates to tilt the same rearwardly.

15 7. A device of the class described comprising, in combination, a pair of skis each having a transverse sleeve at its forward end; a pair of handles each having a tubular bearing portion insertable in one of said sleeves; whereby said 20 handles are pivotally connected to said skis; a frame interconnecting said handles against lateral movement while providing for oscillation of said bearing portions to permit relative angular movement of the skis; and means engageable in 25 the inner ends of said bearing portions and operable to limit such oscillation.

8. A device of the class described comprising, in combination, a pair of skis each having a transverse sleeve at its forward end; a pair of 30 handles each having a tubular bearing portion insertable in one of said sleeves and extending inwardly there through, whereby said handles are pivotally connected to said skis; a frame interconnecting said handles against lateral movement 35 while providing for oscillation of said bearing portions to permit relative angular movement of the skis; and a spreader extending between said skis and having offset ends loosely fitting in said bearing portions to provide for 40 such oscillation while limiting the extent thereof, said offset ends preventing inward displacement of said sleeves from said bearing portions.

9. A device of the class described comprising, in combination, a pair of skis each having a transverse sleeve at its forward end; a pair of 45 handles each having a tubular bearing portion insertable in one of said sleeves and extending inwardly there through, whereby said handles are pivotally connected to said skis; a frame disengageably interconnecting said handles against lateral movement while providing for oscillation of said bearing portions to permit relative angular movement of the skis; and a spreader extending between said skis and having offset ends loosely fitting in said bearing portions to provide for 55 such oscillation while limiting the extent thereof, said offset ends preventing inward displacement of said sleeves from said bearing portions.
